ATTORNEY

UNITED STATES PATENT OFFICE.

HARRY GESSLER, OF NEW YORK, N. Y., ASSIGNOR OF TWENTY-FIVE PER CENT TO
WILLIAM VOGEL, OF NEW YORK, N. Y.

PIPE-BOWL CLEANER.

Application filed January 28, 1925. Serial No. 5,215.

To all whom it may concern:

Be it known that I, HARRY GESSLER, a citizen of the United States, residing at New York city, borough of Manhattan, in the county of New York and State of New York, have invented certain new and useful Improvements in Pipe-Bowl Cleaners, of which the following is a specification.

This invention relates to smokers' appliances and has particular reference to a simple implement or device for scraping and cleansing the inner wall of the bowl of a smoking pipe.

Among the objects of the invention is to provide a device of the character indicated that will be both simple and cheap in construction and of utmost reliability or efficacy in practice irrespective of the size or form of the pipe bowl to be cleansed.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a perspective view of a pipe bowl showing my improved cleaner in operative position.

Figs. 2 and 3 are flat blanks of the two parts constituting the complete device.

Fig. 4 is a front elevation.

Fig. 5 is a side elevation, full and dotted lines showing two different positions of the scraping members.

Fig. 6 is a horizontal sectional detail on the line 6—6 of Fig. 4.

Fig. 7 is a diagram indicating the range of practical operation of the device in relation to the pipe bowl of extremely large or small diameter, the scale of the figure being large to better show the scraping action.

Referring now more specifically to the drawings I show my device as adapted to be inserted endwise directly into the bowl B of a smoking pipe, the device consisting of two relatively simple parts 10 and 11 both

stamped or otherwise formed directly from sheet material such as steel of uniform thickness, thus insuring that the construction is of the simplest and cheapest nature in so far as the material and manner of formation are concerned.

Each of the members aforesaid includes a scraping element and a finger piece. The member 10 thus comprises a blade 12 of flat form and arranged in a plane radial with respect to the main vertical axis of the device, but having along its inner edge a reinforcement flange 13. The upper end of the blade 12 may be cut and turned from the plane of the finger piece 14, along a line 15 of the blank shown in Fig. 2. Adjacent to the lower edge portions of the finger piece 14 are formed two bearing slots 16 spaced equally from opposite sides of the vertical center of the finger piece and in the same line perpendicular to said axis. After the member 10 is formed from the flat blank as is shown in Fig. 2 it is shaped to bring the blade 12 into a plane at right angles to the remainder of the member, the plane thereof coinciding with the axis aforesaid and as shown in Figs. 4 and 5. It is preferred also that a stiffening rib be formed downward along the center of the finger piece as shown at 17, said rib running into the blade portion.

The other part of the device is stamped flat as shown in Fig. 3 and comprises a double blade portion 18 and a finger piece 19, the general form of which is similar to the finger piece 14. The two edge portions of the blade section 18 are of equal width and are symmetrical with respect to the vertical axis of the member and extend laterally from said axis in opposite directions. This finger piece 19 also is preferably provided with a stiffening rib 20 extending downward along said axis. At the upper end of this rib or at any other convenient point is formed a hole 21 for attachment of the device to a key ring or the like. Instead of slots 16 this finger piece 19 is provided with bearing studs 22 struck out from the body of the finger piece remote from its edges and adapted in the completed article to stand substantially at right

angles to the plane of the finger piece 19. Each stud or fulcrum includes a pair of shoulders 23 between which are one or more tongues 24 which project through the slots 5 16 and are bent over or upset at the front side of the finger piece 14 for the purpose of holding the parts together while the inner face of the finger piece 14 has a rocking action upon said shoulders, an action that 10 is very easy because the bearing shoulders act substantially as a knife edge bearing, the line of all the shoulders constituting the axis of the hinge connecting the two members. It will of course be understood that 15 the slots 16 are slightly wider than the thickness of the metal of the tongues and that the tongues are long enough to permit free rocking movement. See Fig. 5. The neck portions 25 of the bearing studs are integral 20 with the lower edge portions of the finger piece 19 and are located at about the same position with respect to the finger piece 19 as are the slots 16 in the other finger piece. In addition to the striking out of the studs 25 22, the blade portion 18 of the member 11 is convexed toward the central axis of the device, the cross section being of any suitable form or curvature and with the edges of these blade portions left sharp and square 30 as formed by the stamping dies.

The point portions of all the scraping blades 12 and 18 are rounded but narrow enough for the points thereof to enter freely to the bottom of the smallest pipe bowl when 35 the device is inserted directly thereinto as suggested in Fig. 1. After being so inserted to the bottom of the bowl the finger pieces of the device are grasped between the thumb and finger of either hand while the 40 pipe is held in the other and a relative rotation between the scraper and the bowl is then given. The grasp of the device between the thumb and finger will insure directly and practically automatically the 45 spreading contact of the point portions of the scraping blades as suggested by dotted lines in Fig. 5, according to the form of the bowl and with a force proportional to the pressure applied upon the outer surfaces 50 of the finger pieces. In other words, the greater the pressure upon the finger pieces, the more intensive will be the scraping action on the interior of the bowl. In the case of a large bowl, any portions of the inner 55 surface thereof that are not scraped when the device is introduced as deep as it may go will be reached and scraped by a continued rotation of the device in the bowl and withdrawal thereof upward from the 60 bottom of the bowl. The diagram of Fig. 7 shows in full lines the action of the scraping edges α and α' , all three of which edges are sure to engage the interior surfaces, while in dotted lines is shown the action of 65 the scraping blades on the surface of a small

bowl. The action of the edge α' is practically the same in all sizes of bowls, but by comparison of the action of the edges α on the large and small bowls, it will be observed that one of the edges α may have a more 70 effective scraping action than the other, but the edge that is the more effective will depend upon the size of the bowl. More specifically stated, when operating upon a large 75 bowl the leading edge on the concave side of the blade 18 will have a sharper cutting effect than the trailing edge, whereas in the small bowl the leading edge on the convex side will have a more direct cutting action. Hence each portion of the double blade has 80 two scraping edges α selectively operative according to variations in diameter of the bowl B. But as before premised in all cases all three blade portions contribute toward the desired result as a result of the pressure applied by the thumb and finger on 85 the finger pieces.

It will thus be noted that the device consists of but two parts which are made readily and cheaply as by stamping from sheet metal of uniform thickness and with bearing means stamped out at an angle from one of the parts and serving as fulcrums or pivot means upon which the other part is mounted or hinged loosely for tilting around the axis of the articulation, the two parts acting in this manner as levers of the first class.

I claim:

1. A pipe bowl cleaner comprising two 100 blade members hinged together tiltably, each member including a finger piece extending therefrom beyond the axis of the hinge, and one blade member having a plurality of scraping edges selectively operative according to variations in diameter 105 of the bowl.

2. A pipe bowl cleaner comprising two 110 blade members hinged together tiltably, each member including a finger piece extending therefrom beyond the axis of the hinge, one blade member having a greater number of scraping edges than the other.

3. A cleaner as set forth in claim 2 in 115 which one blade member has twice as many scraping edges as the other.

4. A sheet metal pipe bowl cleaner consisting of two parts, each having a finger piece, the parts being articulated together and acting as levers of the first class, one part having shouldered fulcrum means struck outward therefrom at an angle to the main part and remote from the edges thereof, and the other part being apertured to receive loosely and tilt upon said shouldered fulcrum means.

5. A pipe bowl cleaner comprising two 120 parts, each part consisting of a blade portion and a finger piece integral therewith, one part having a plurality of studs struck 125

therefrom in the same direction and having bearing shoulders extending along the line of connection between the two parts, and the other part having openings to receive loosely the studs and to bear against said shoulders, the studs including means to retain the parts in assembled position.

6. A device as set forth in claim 5 in which each stud has two shoulders, all the shoulders being in the same line. In testimony whereof I affix my signature.

10

HARRY GESSLER.
